CHARCOAL FIRE EXTINGUISHER

Jerome P. Homola, 2215 Earl Lane, South St. Paul, Minn.

Filed Dec. 7, 1962, Ser. No. 72,771

Term of patent 14 years

(Cl. D81—10)

FIG. 1

FIG. 2

FIG. 3

FIG. 4

FIGURE 1 is a top plan view of a charcoal fire extinguisher, showing my new design;

FIGURE 2 is a front elevational view of the same;

FIGURE 3 is a side elevational view of the same;

FIGURE 4 is a bottom plan view of the same, and

FIGURE 5 is a top perspective view of the same.

I claim:

The ornamental design for a charcoal fire extinguisher, as shown.
